UNITED STATES PATENT OFFICE.

LEO F. MILLARD, OF WHITEWATER, WISCONSIN.

CORE-BOX USED IN THE ART OF MOLDING FOR METAL-CASTING.

No. 903,102.

Specification of Letters Patent.

Patented Nov. 3, 1908.

Application filed May 16, 1908. Serial No. 433,332.

To all whom it may concern:

Be it known that I, LEO F. MILLARD, a citizen of the United States, residing at Whitewater, in the county of Walworth and 5 State of Wisconsin, (whose post-office address is Whitewater, Wisconsin,) have invented certain new and useful Improvements in Core-Boxes Used in the Art of Molding for Metal-Casting, of which the 10 following is a specification.

My invention relates to boxes used in molding cores with depressions or cavities in them; and the objects of my invention are to provide a box which can be firmly and conveniently held in place during the process of molding, and in which the interior projections, which produce the depressions or cavities in the core, are automatically drawn out of the core before the box is opened, thus insuring unbroken surfaces in and clean cut edges about the depressions or cavities made in the core. I attain these objects by use of the mechanism illustrated in the accompanying drawings in which,—

Figure 1 is a view of my improved core box with the several parts all held together firmly and in proper position to receive material for molding a core; Fig. 2 is an exterior view of a longitudinal section of the box showing the automatic projections drawn out; Fig. 3 is an interior view of a longitudinal section of the box showing the position of the automatic projections on the interior surface of the box when held in position for molding as shown in Fig. 1; and, Fig. 4 is a view of one of the automatic projections detached from the box.

Similar letters refer to similar parts throughout the several views.

The core box A consists of a shell made 40 of one or more parts, $a-a'$ having openings $b-b'$ etc. through the shell through which the automatic projections c, c' etc. work. These projections consist of a plunger d and a spring e Fig. 4, fastened to the box by a 45 screw f . When the box is closed a clasp g is forced over the same holding the springs e down as shown in Fig. 1, in which case the plungers d are pushed into the core chamber h and held in position as shown in Fig. 3. 50

The core chamber h is then filled with the molding material and when properly packed the clasp g is removed allowing the springs e to draw the plunger d out of the core, when the box may be opened and the core 55 removed without interference from the projecting plungers.

I do not confine my invention to the particular form of construction herein shown, but may use any shaped parts and any combinations of mechanical parts by which substantially the same results are produced. 60

Having thus described my invention what I claim as new and desire to secure by Letters Patent is:—

A core box consisting of a shell composed of one or more pieces having openings through which pieces, actuated by springs, work to form interior projections all held together by a surrounding clasp, substantially as described and shown, for the uses 65 and purposes mentioned. 70

LEO F. MILLARD.
